UNITED STATES PATENT OFFICE.

FRANK WATKINS, OF BURTON, WASHINGTON, ASSIGNOR OF ONE-HALF
TO MILLARD F. SHAW, OF BURTON, WASHINGTON.

SHARPENING ATTACHMENT FOR CUTTING-TOOLS.

SPECIFICATION forming part of Letters Patent No. 777,269, dated December 13, 1904.

Application filed October 8, 1903. Serial No. 176,279. (No model.)

To all whom it may concern:

Be it known that I, FRANK WATKINS, a citizen of the United States, residing in Burton, county of King, and State of Washington, 5 have invented certain new and useful Improvements in Sharpening Attachments for Cutting-Tools, of which the following is a specification.

My invention relates to the construction of 10 the handles of cutting-tools so that a whetstone may be detachably secured thereto; and the objects of my invention are, first, to provide a tool-handle which will always have the means for sharpening the tool at hand, and, 15 second, which will so protect the whetstone at all times that there will be practically no danger of its becoming cracked or broken. I attain these objects by the device illustrated in the accompanying drawings, in which—

20 Figure 1 is a top view of a pocket-knife having my whetstone secured in place in the handle. Fig. 2 is a section of same. Fig. 3 is a side view of the whetstone detached from the knife-handle. Fig. 4 is a partial top view thereof, and Fig. 5 is a side view of the knife-handle with the whetstone removed therefrom.

Similar letters of reference refer to similar parts throughout the several views.

I have illustrated my invention as applied 30 to a pocket-knife and will describe it in detail, as shown on the drawings; but I do not wish it to be understood that I confine its use to pocket-knives, but, on the contrary, claim that it can with but very slight modifications 35 be used in connection with any cutting-tool which has a space large enough to receive a whetstone adapted to sharpen it.

The knife illustrated is a single-bladed pocket-knife having a blade A pivoted in the 40 usual manner at one end at B to the head C of the handle. This handle is usually constructed with its sides of bone; but in my invention only one side D is of the usual construction, the other side being formed of a 45 metal piece E, engaging the head C and the end F and bent so as to conform to the outline of the side of the knife and having the

whetstone G secured to its inner side, so that it lies between the piece E and the side H of the blade-recess. The parts C and F of the 50 handle are provided with grooves I, which I prefer to make wedge-shaped, as shown in dotted lines in Fig. 5. Into these grooves I project the ends J of the metal casing E of the whetstone. These ends J, I also prefer to 55 make wedge-shaped and slightly inclined, as shown in Figs. 3 and 4, so as to better engage the sides of the grooves I.

The whetstone G is secured by any suitable means to the piece E—as, for instance, it 60 might be cemented thereto, or the sides of the piece E might be bent around the stone to secure it in place. The whetstone is protected from damage at all times by the casing E, in which it is secured.

My device is used in the following manner: When the blade is dull, the piece E, with the whetstone G secured to it, is slid along the side H until the ends J are disengaged from the grooves I, and it is then held so that the blade 70 can be sharpened. When this has been done, the whetstone G is turned so that its face will come against the side H, and the ends J of the piece E are made to engage the grooves I and then it is pushed to its normal position. 75

What I claim, and desire to secure by Letters Patent, is—

1. In combination, a cutting-tool handle having a recessed surface on one side thereof with grooves in the ends of the recess, a 80 removable protecting-frame engaging said grooves and bent to form a space between it and said recessed surface, and a sharpening medium secured to said protecting-frame within said bends thereof whereby said space 85 is filled substantially as shown and described.

2. In combination, a cutting-tool handle having a recessed surface on one side thereof with grooves in each end of the recess, said 90 grooves being wedge-shaped, a sliding protecting-frame having wedge-shaped ends adapted to engage and slide in said grooves and being bent to form a space between it and said recessed surface, and a sharpening me-

dium secured to said protecting-frame within said bends thereof in such manner that said space is substantially filled.

3. In combination, a cutting - tool handle having a recessed surface on one side thereof, a sharpening medium, and a protective casting carrying the same and adapted to secure the sharpener within the recess as set forth.

In testimony whereof I have signed my name to this specification in the presence of two subscribing witnesses.

FRANK WATKINS.
